UNITED STATES PATENT OFFICE.

ORESTE FRANCHINI, OF TURIN, ITALY, ASSIGNOR TO GIUSEPPE RATTI, OF TURIN, ITALY.

GOGGLES.

Application filed May 5, 1926, Serial No. 106,927, and in Italy May 7, 1925.

The present invention relates to protecting goggles comprising adjustable means for connecting the two glass-carrying frames and has for its object an adjustable means 5 for varying the spacing between the glasses of the goggle to suit the wearer's eyes.

On the annexed drawing is shown by way of example an embodiment of the present invention, and

10 Figure 1 is a fragmentary front view of a goggle with the device according to the present invention in locked condition;

Figure 2 is a transverse section on line 2—2 of Fig. 1;

15 Figure 3 is a view similar to Fig. 1, with the device parts in released position;

Figure 4 is a transverse section on line 4—4 of Fig. 3.

As shown in said drawing, each of the 20 frames 1—14 carrying the goggle glasses is pivotally connected with a stem 2—12 of conventional shape; one of said stems, as 2, is connected with a channel section part 3 having an end abutment 4, and the other 25 stem 12 is connected with a part 13 adapted to slide within said channel section part 3 and under the abutment 4, and having a pin 5 adapted to engage said abutment 4.

The frames 1—14 are thus interconnected in such a manner as their respective distance may be modified at will by causing the parts 3 and 13 to slide into or out of each other.

In order to fasten the parts in the preferred position, a blade spring 6 is fastened 35 on the channel section part 3 said spring extending along and adjacent to said part 3 over the part 13 and having a stud 7 intended to engage recesses or notches 8 provided in sliding part 13.

40 The side flanges of channel part 3 provide extensions or lugs 9 in which is pivoted a rectangular or noncylindrical member 11 having a manipulating head 10, the shape and size of said member 11 being such as in 45 a position it leaves the spring 6 free to recede from said part 13 with its stud 7 released from recesses 8 of said part 13, while by rotating said member 11 by means of its head 10 through an angle, said blade 6 is 50 forced towards the sliding part with its stud 7 engaged in one of recesses 8.

In practice, when the flat face of the 55 rotary member 11 bears on the spring, said member cannot be shifted from said position without depressing the spring until the cor-

ner is enabled to move forward, and therefore the resiliency of the spring is to be overcome, the member 11 thus is a self-locking cam member.

Thus, assuming the parts arranged in the 60 position of Figs. 3 and 4 and it being desired to shorten the distance between the parts 2—12 and frames 1—14, the sliding part 13 is moved longitudinally into the channel section part 3 and then the member 65 11 is rotated through 90° to carry the parts to the position of Figures 1 and 2, in which the spring 6 is forced by edge of member 11 on the sliding part 13 with its stud 7 engaged in one of recesses 8 of channel part 3. 70

Of course the present invention is not restricted to the embodiment described and illustrated, the construction and arrangement of the parts being capable of modifications within the spirit of appended claims. 75

What I claim as my invention and desire to secure by United States Letters Patent is:—

1. A goggle comprising two frames for carrying transparent material, a first part 80 connected with one of said frames, a second part connected with the other one of said frames, means providing a sliding engagement of said parts with each other, a resilient member connected with said first part 85 and extending along the same, cooperating engaging means on said resilient member and said second part, and a member mounted to rotate on said first part and having noncircular shape with respect to its axis of 90 rotation, said member cooperating with said resilient member to lock it in engagement with said second named part.

2. A goggle comprising two frames for carrying transparent material, a channel section part connected with one of said frames, a part connected with the other one of said frames and adapted to slide in said channel part, a resilient member connected with said channel part and extending along the same, 100 cooperating engaging means on said resilient member and sliding part, a member mounted to rotate on said first part and having noncircular shape with respect to its axis of rotation, said member cooperating with said resilient member to lock it in engagement 105 with said sliding part.

3. A goggle comprising two frames for carrying transparent material, a first part connected with one of said frames, a sec- 110

ond part connected with the other one of said frames, means providing a sliding engagement of said parts with each other, a resilient member connected with said first 5 part and extending along the same, cooperating engaging means on said resilient member and said second part and a self-locking cam member mounted to rotate adjacent said resilient member and adapted to lock it in 10 engagement with said second named part.

4. A goggle comprising two frames for carrying transparent material, a first part connected with one of said frames, a second part connected with the other one of said 15 frames, means providing a sliding engagement of said parts with each other, a resilient member connected with said first part and extending along the same, cooperating engaging means on said resilient member and 20 said second part, and a member having rectangular cross section and mounted to rotate adjacent said resilient member, said rec-

tangularly cross-sectioned member being adapted to be attached in a position to leave said resilient member free and to another position to lock said resilient member in engagement with said second named part. 25

5. A goggle comprising two frames for carrying transparent material, a first part connected with one of said frames, a second part connected with the other one of said frames, means providing a sliding engagement of said parts with each other, a spring blade connected with said first part, engaging means carried by said blade and adapted 30 to engage cooperating engaging means of said second part, and a cam member mounted to rotate adjacent said blade and adapted to bring and maintain said engaging means 35 of said blade and part in engagement with each other. 40

In testimony whereof I have signed my name to this specification.

ORESTE FRANCHINI.
